EDWARD A. STIGGINS, OF BEVERLY, MASSACHUSETTS, ASSIGNOR TO UNITED SHOE MACHINERY COMPANY, OF PATERSON, NEW JERSEY, A CORPORATION OF NEW JERSEY.

LASTING AND STAPLING MACHINE.

1,163,598.

Specification of Letters Patent.

Patented Dec. 7, 1915.

Application filed April 28, 1911. Serial No. 623,860.

To all whom it may concern:

Be it known that I, EDWARD A. STIGGINS, a citizen of the United States, residing at Beverly, in the county of Essex and State of Massachusetts, have invented certain Improvements in Lasting and Stapling Machines, of which the following description, in connection with the accompanying drawings, is a specification, like reference characters on the drawings indicating like parts in the several figures.

This invention relates to lasting machines. While in its broadest aspect the invention is not limited to use with any particular construction or type of lasting machine, for the purpose of illustration it is herein shown and will be described as embodied in that type in which the upper is worked over the last by repeated operations and secured in overworked position by fastenings as the work progresses. Such a machine is disclosed, for example, in United States Letters Patent No. 584,744, dated June 15, 1897.

In the machine shown in the prior patent referred to and others of this type, when lasting welt shoes the upper is stretched over the last and its margin placed against the lip or rib of the innersole and is secured in position by tacks which are driven by a driver from a reciprocating tack carrier which is advanced over the edge of the shoe during each complete operation of the machine to present the tacks in proper position to be driven. The tacks for thus securing the upper to the innersole are driven nearly perpendicular to the plane of the shoe bottom, and in carefully lasted shoes of the better grades are driven fairly close together for the purpose of holding the upper securely and snugly about the last. When allowed to remain during the subsequent operation of permanently uniting the upper and welt to the innersole by the inseam sewing machine, these tacks offer an obstruction to the movements of the needle and awl, which frequently encounter the tacks, and are bent or broken off. It has been proposed, with a view to obviating this objection to the use of lasting tacks, to allow the shoes to remain in lasted condition for a considerable length of time until the upper has become set in the position to which it has been lasted, and to then withdraw the lasting tacks, and drive, at selected points about the shoe, a lesser number of "stay"

tacks which serve to hold the upper in position temporarily during the inseaming operation. While this expedient remedied, to some extent, the objection above pointed out, it nevertheless did not entirely prevent an occasional breakage of the needle or awl of the inseaming machine, as the stay tacks were also driven substantially perpendicular to the plane of the innersole and hence were directly in the path of the needle and awl as they passed through the between substance in a substantially horizontal direction.

With a view to entirely dispensing with the use of tacks as the means for temporarily securing the upper in lasted position in the manufacture of welt shoes, turn shoes, or any other shoes employing a sole provided with a rib, lip or shoulder, a very important feature of the present invention lies in the provision of means for securing the over-worked upper to the innersole during the lasting operation by separate fastenings which act transversely of the lip and hence offer no substantial obstruction to the inseam sewing operation. While the invention in its broadest aspect contemplates utilizing, in co-operative relation with lasting means, mechanism for applying separate fastenings of any form which will act substantially transversely of the lip to secure the over-worked upper thereto, I prefer to use for this purpose fastenings which pass through the upper and the lip, or between substance of the innersole, in order that the upper may be reliably secured in lasted condition without danger of slipping. Preferably such fastenings will be applied separately, as the lasting operation progresses, so as to hold securely in position each section of the margin of the upper as it is stretched about the last and laid against the lip or shoulder of the innersole by the lasting instrumentalities, and preferably, also, such fastenings will be so placed as to lie above the plane of movement of the inseamming needle in order to further reduce the probability of the fastenings being encountered by the needle or awl.

The machine selected for illustration of the invention is shown as embodying mechanism for forming and inserting staples which may be made of wire of such fine gage as to offer as little obstruction as possible to the movement of the inseam sewing machine needle, but which will, nevertheless, be of

sufficient strength to effectively secure the upper, while under lasted tension, to the lip of the innersole and hold it in such position until the completion of the inseaming operation. In such machine the staples are formed, and are driven through the over-worked upper and lip of the innersole, at the completion of each operation of the lasting devices.

10 In machines of the type shown in the prior patent referred to, when the toe portion of a welt shoe is to be lasted the operator effects, through the movement of a knee lever, the proper positioning of the usual work

15 pressers which are then advanced to smooth down the overlapped or plaited portions of the upper, and by the same movement he renders operative the mechanism for giving to the pincers the movements which plait

20 the leather to dispose of its fullness at this point. The greater thickness of the upper materials at the toe of the shoe renders it desirable to provide fastenings of greater length for securing the stock at the toe than

25 are used for securing it along the sides, and to this end a feature of this invention consists in providing mechanism for controlling the length of the fastenings simultaneously with the usual adjustments of the

30 machine made for lasting at the toe, and along the sides of the shoe. While there are many ways in which this might be accomplished, it is, as herein illustrated and described, embodied in a construction where

35 the slide which is moved by the usual knee lever to advance the thin work-pressers to the position where they may be operated by their driver, has connection with the instrumentalities which control the length of the

40 fastenings to be formed by the stapling mechanism. The construction and arrangement of these parts are such that when the slide is moved to advance the work-pressers to operative position preliminary to lasting

45 the toe portion of a shoe, adjustments of the fastening-forming mechanism are simultaneously made to effect the formation of long staples; and when the slide is moved in a reverse direction to withdraw the work

50 pressers from operative position, before lasting the sides or other portions of the shoe, the fastening-forming mechanism is adjusted for the formation of short staples. As the advancement of the work pressers for

55 lasting at the toe is, in the machine referred to, accompanied by the necessary adjustment of the pincer-actuating mechanism to cause them to plait the upper, it will be understood that these latter adjustments are

60 also made simultaneously with those which effect the production of long staples for securing the upper materials at this part of the shoe.

The mechanism referred to for producing, 65 through adjustments of the slide which ad-

vances the work pressers, long staples to secure the upper about the toe and short staples to secure the upper along the sides of a shoe, is useful in those cases where it is desired to secure the upper to the lip or between substance of the innersole continuously around the shoe, including the toe portion. Under modern methods of lasting welt shoes as practised in most factories the overworked upper is not secured about 75 the toe by lasting tacks, but is bound in by a continuous binder, whose ends are usually anchored to tacks which are driven into the last at opposite points and a suitable distance from the end of the shoe. In order, 80 therefore, to permit the use of a continuous binder at the toe this invention includes as a feature means, under the operator's control, for suspending, when desired, the formation of the staples as the machine is adjusted for lasting the upper at the toe so that no staples will be driven into the work at such time, and the operator may perform the usual manipulations to secure the over-worked upper material to the lip by a continuous binder, in lieu of staples. In the machine herein illustrated, such means comprises a yielding pawl which is in connection with the slide, heretofore referred to, for effecting the advancement of the work- 90 pressers, which pawl is arranged to be so positioned as to obstruct, or permit, at the operator's will, the operation of a member of a clutch which forms part of the feeding mechanism for the wire from which the 95 staples are formed. If it be desired to secure the upper by staples at the toe, the pawl will be so positioned that, as the slide moves to render operative the work pressers for toe lasting the pawl will not be advanced 100 sufficiently far to obstruct the operation of the wire feeding mechanism; on the other hand, if toe-wiring is desired, the pawl will be moved to a different position in which as the slide is shifted preliminary to toe lasting the pawl will be caused to engage with the wire-feeding clutch member and effect a suspension of the wire supply to the stapling mechanism, so that staples will not be formed. 110

Another advantageous feature of the invention in connection with the securing of the upper at the toe by a continuous binder is found in the capacity of the machine to apply the staples to the ends of such a binder 120 for anchoring it to the last. This may be accomplished by holding an end of the binder in position to be straddled by the ~~last~~ staple which is to be driven prior to lasting about the toe, causing said staple to be driven upon the wire, suspending the operation of stapling, then continuing the lasting operation about the toe and securing the overworked upper in the usual manner with the binder, and finally by anchoring the 125 130

other end of the binder to the last by another staple. This procedure obviates the necessity for driving and withdrawing the usual objectionable anchoring tacks, and results in the effective fastening of the binder to the last by devices which are so located that they will offer no obstruction to the movements of the needle or awl of the inseam sewing machine, and hence obviates the necessity of removing such devices from the shoe prior to the operation of said machine.

These and other features of the invention, including important details of construction and combinations of parts, will be hereinbelow more particularly described and claimed.

In the drawings: Figure 1 represents, in side elevation, a lasting machine embodying the present invention; Fig. 2 is a sectional plan view, somewhat enlarged, on the broken line 2—2, Fig. 1; Fig. 3 is an enlarged detail view, in side elevation, of the machine shown in Fig. 1, illustrating the wire feeding devices, and the controlling mechanism therefor; Fig. 4 is an enlarged perspective view of the staple forming and driving mechanism; Fig. 5 is a detail view, showing parts of the staple forming devices; Fig. 6 is a sectional plan view of the parts shown in Fig. 5; Fig. 7 is a sectional detail view, illustrating the operation of the staple driving and clenching tools; Fig. 8 shows the fore part of a lasted shoe with the upper secured at the sides by fastenings in the manner contemplated by this invention, and at toe by a binder anchored to tacks; Fig. 9 shows the fore part of a lasted shoe, with the upper secured at the sides and about the toe, continuously, by staples in the manner contemplated by this invention; and Fig. 10 is a detail view illustrating how the ends of a continuous toe binder may be anchored by staples driven through the upper and lip and transversely of the lip.

The column of the machine A supports a head B in which are bearings for the main shaft 3, which is driven by power derived from a suitable source and applied through a belt to the pulley 1. The grippers 9 are suspended from the front end of the lever 2, and are lowered into position for seizing the upper and are raised for pulling the upper by a cam which actuates said lever, as described in the Letters Patent before referred to. The grippers are also opened and closed at the proper times to grip and release the upper by mechanism substantially such as described in said patent. The machine is also shown as having the usual knee lever 15 which has connection with the mechanism for imparting to the grippers the movements necessary to plait the upper at the toe part of the shoe, when said lever is moved in the proper direction therefor, or to discontinue such movements when the knee lever is

shifted in a reverse direction. The lever 15 also has connection with the slide 13 which acts to advance the work-pressing or wiping members 11 to a position where they will be caused to reciprocate by their driver 70 to wipe or smooth the upper about the toe, such positioning of the work pressers 11 being effected by the same movement of the knee lever which causes the grippers to plait the upper. These operations are all 75 fully described in said prior patent.

The slide 13 is herein shown as provided with a rack 21 which engages a toothed segment 23 carried by an arm 25 which is fast to a vertical rock shaft 27 movable in bearings carried by the machine frame. The upper end of the shaft 27 is provided with a segmental gear 29 which engages a segmental gear 31 at one end of an arm 31. The arm 31 is rigid with a vertical rock shaft 33, which is supported in bearings sustained from the main frame, and a lower arm 35 is secured to the rock shaft and connected through an adjustable eccentric stud 38 with one end of a link 37. The other end of this 90 link is connected to a slide 39, within which is slidably mounted a spring-pressed pawl 40. This pawl is arranged to engage ratchet teeth 42 on the periphery of the inner or driven member of a ball clutch 65, which 95 forms part of the wire feeding mechanism. The operation of these several parts will be described hereinafter.

A vertical shaft 41, supported in bearings carried by the frame, is provided with a worm gear 43 which is driven by a spiral gear, (not shown) fast on the main shaft 3. The shaft 41 has at its lower end a crank pin 45 which is connected through a link 47 and pin 51 to one end of a lever 49. The 105 inner end of this lever is guided in a slot 53, formed in a rigid part of the frame, and a slot 59 between the ends of the lever receives a movable fulcrum pin 55 which is carried by an arm 57 rigidly attached to the rock shaft 33. The outer end of lever 49 is shown as having a slidable block 61 which moves in a transverse guideway at the end of a rack 63, said parts forming a self-adjusting connection between the lever and rack to permit the necessary amount of transverse motion of the lever relative to the rack as the lever transmits reciprocatory movements to the rack. The teeth of this rack engage the teeth formed on the 110 periphery of the driving or ring member 65^a of the one-way ball clutch, the inner or driven member of which is fast to one end of a shaft 66 which is supported for rotation in bearings carried by the frame of 120 the machine. The other end of this shaft carries a wire feeding disk 67, having a wire-receiving groove 69 in its periphery. A wire retaining disk 71 is supported for free rotation on an arm 73, which is piv- 125

oted to the frame, and a spring 75, confined between the frame and an arm 74, which is rigid with the arm 73, normally acts to hold the disk 71 in contact with the feeding disk 67. It will be understood from the construction described that motion transmitted to the shaft 41 from the main shaft of the machine will effect a reciprocation of the rack 63, and an intermittent rotary motion will be imparted from the rack to the clutch member 65^a, and thence to the wire feeding disk 67.

An arm 77, shown by dotted lines in Fig. 2, is rigidly attached at one end to the shaft 33, and at its opposite end is connected with a link 79, which is in turn connected with a lever 81, pivoted to the frame, and carrying at its end a segmental gear 83. The gear 83 meshes with a rack 85 on the rear of a slide 87 which is suitably supported for movement in the machine frame. The slide 87 carries a bearing 89 in which is mounted the rock shaft 91 of a cutter member 93, see Fig. 4. A co-operating cutter member 95 is attached to a projection rigid with the bearing 89. Attached to the shaft 91 is an arm 97 which carries a cam roll 99 engaging a cam slot 101, which is shown as being formed in a block carried by the staple-forming slide 103, Fig. 4. The slide 103 is mounted for reciprocating movements in guideways carried by the main frame, and when moved will, through the mechanism described, operate the cutter member 93 in a manner to be fully explained hereinafter.

A lever 8, pivoted to the frame, Fig. 1, carries at one end a cam roll 6 which enters a groove in the cam 5, and at its opposite end the lever is connected with a slide 105, Fig. 3, which is guided for reciprocating movements in the frame of the machine, and carries at its outer end a rack 107, Fig. 2. This rack is in mesh with a pinion 113, Fig. 4, fast to a rock shaft 109, sustained by bearings in the frame. The shaft 109 carries also a pinion 115, and at its end opposite that which carries the pinion 113, has a rigid arm 117. The lower side of the staple-forming slide 103 is provided with a rack 118, which engages the pinion 115, so that any oscillating motion imparted to this pinion is applied to reciprocate said slide. A staple-forming anvil 121 is rigidly attached to the machine frame, and the two members of a bifurcated stripper 123 are arranged to slide vertically upon and in close engagement with opposite sides of the anvil. The members of the stripper are provided with rack teeth which mesh with similar teeth at the end of an arm 125, see Fig. 4. This arm is rigidly mounted upon the end of a shaft 127 which oscillates in a fixed bearing in the frame, said shaft having at its opposite end an arm 129 which carries a

roll 131. The roll 131 is located in the path of movement of the arm 117, heretofore described.

The staple driver 119 is shown as secured in a split block 122 by a clamping screw 124. The block 122 carries a toothed slide 126 which co-operates with the segmental toothed portion of a pinion 127, which is secured to a rock shaft 129, mounted in a bearing in the main frame. The shaft 129 also carries a pinion 131 whose teeth are in mesh with a rack 135 at the end of the driver bar 133. This bar is connected with a rod 14, Fig. 1, whose upper end is engaged by an arm 12 which is actuated by a spring 10, substantially in the manner in which similar parts are operated in the prior patent before referred to. The bar 133 carries a projection which engages a drop cam 7, fast on the shaft 3, so that as the cam rotates the bar is first lifted against the tension of spring 10, and is then released, whereby the spring reacts and imparts a driving stroke to the driver bar. These movements occur during each complete cycle of operations of the machine.

The wire from which the staples are formed is supplied by a reel 137, Fig. 2, which is rotatably carried by a suitable fixed support. The reel is provided with a wire guide 139, and attached to the frame is another wire guide 141 which is located near the feed roll 67. After passing through these wire guides and over the feed roll, the wire *w* enters and passes through a duct 143, which is covered by a plate 145, the duct terminating at a point near the cutter members 93, 95.

The driver passage 147 is formed at its top and sides partly in the staple-forming slide 103, and partly in a member 151 which is secured to the slide 103, see Fig. 4. A plate 149, shown in Figs. 4, 5 and 6, attached to the slide 103, is shaped to embrace the sides of the anvil, and assists therewith in forming a continuous lower surface of the passage 147 when the parts are as shown in Figs. 3 and 6. A recess 153 is formed in the member 151, beneath the plate 149 of a width slightly in excess of the length of the anvil, in order to permit a free passage of the wire across the bending surface of the anvil during the formation of a staple. A slot 155 is formed in the slide 103 in order to allow the free passage of the slide over the anvil and stripper. The slide is provided with bending corners 157 which are constructed to bend the wire over the anvil, in the operation of forming a staple. The staple forming slide 103 terminates in a forwardly projecting nose as shown in Fig. 3 which is shaped to fit snugly against the upper and force it into close engagement with the angle at the junction of the feather edge and lip of the sole. As shown in Fig. 1, 186

an arm 159 is carried by a bracket attached to the frame and projects rearwardly in position to engage the inside of the lip, so as to sustain the shoe against the pressure of the staple-driver, and also to clench the ends of the staples as they are driven through the upper and lip. This operation is illustrated in Fig. 7.

The eccentric stud 38 heretofore referred to as connecting the arm 35 with the link 37 is provided with a milled handle portion 38^a which carries a spring-pressed locking pin 38^b for engaging suitable recesses in the bearing in which the stud turns, so as to hold the stud in either of its positions of adjustment. By turning the eccentric stud 38 in one direction the pawl 40 will be withdrawn to a position where it can, in no position of the slide 13, engage the teeth 42 of the clutch member so as to interfere with the feeding of wire to the stapling mechanism. When the stud is so adjusted the operations of forming and driving staples will continue uninterrupted during the lasting of the entire shoe, so that the upper will be secured by staples at the toe, as well as along the sides, and, if desired at the heel. By turning the stud 38 to a different position the pawl 40 will be projected forward to such an extent that when the slide is adjusted for toe lasting the pawl will engage the teeth 42 of the clutch member, and prevent the operation of the wire feeding devices, thereby suspending the driving of staples.

In the use of the machine, if the lasting operation is to begin at the sides of the shoe, the operator preliminarily moves the knee lever 15 to shift the slide 13 in the direction of the arrow in Fig. 2, which effects a movement of the work-pressers to bring them out of position for operation. The same movement of the slide 13 effects a shifting of the fulcrum pin 55 of the lever 49 in the slot 59 toward the end of the lever which is nearest to its connection with the feed-actuating rack 63, whereby the feeding movements imparted by the lever to the disk 67 will be shortened. The connections between the lever 25 and the cutters, comprising the arm 77, link 79, lever 81, and slide 87 will at the same time operate to move the cutters nearer to the anvil, so that short staples will be formed for use at the sides of the shoe, it being understood that the described change in location of the cutters at the same time that a shorter length of wire is fed will result in maintaining uniformity in the length of the legs of the staples. The operator then steps on the usual treadle, which effects, through the clutch, rotation of the main shaft 3 carrying the several cams, for imparting to the various mechanisms their necessary movements in the lasting and staple-forming and driving op-

erations. It being assumed that the reel 137 has been supplied with wire, such wire is led through the guides 139 and 141 into the groove 69 of the feed roll, and is held therein by the spring-pressed disk 71, and from this point is led through the duct 143, and past the cutter jaws through recess 153, beneath the plate 149, until the end extends a predetermined distance beyond the anvil. A forward movement imparted to the staple forming slide 103, by the cam 5, and its connections, first causes a depression of the arm 97 and the movable cutter member is thereby actuated to sever a length of wire for one staple. Further movement of the slide 103 grips this length of wire between the two bending corners 157 of the slide and the anvil, and the continued movement of the slide bends the wire around the anvil into the form of a staple, the parallel side members of which lie, at this stage, between the side walls of the recess 153 and the sides of the anvil. The slide 103 in its forward movement carries the plate 149 with it, and when the plate has nearly passed over the stripper the arm 117 will have reached the roll 131. When the arm engages the roll a continued movement of the parts raises the stripper until its top surface is level with the lower surface of the passage 147, which introduces the formed staple into the driver passage. Prior to these several operations, a shoe has been presented, as shown in Fig. 1, to the lasting instrumentalities, and a section of upper has been seized by the grippers, and worked over the last in position to be secured to the innersole. The staple forming slide 103 reaches the limit of its forward movement following such overdraw movement of the lasting pincers, and the nose of the slide then presses the over worked upper tightly into the channel crease and against the lip. At this time, the cam 7 releases the driver bar which forces the formed staple out of the passage 147 and through the upper and between substance of the innersole, in a direction transverse to the lip, the ends of the staple meeting the resistance of and being clenched by the clenching tool 159, as shown in Fig. 7. The several parts are then returned to their initial positions, and the described operations are repeated along the side of the shoe, each successive portion of the upper being worked into lasted position and secured there by a staple.

When the toe of the shoe is reached, if it is desired to secure the upper here by staples also, as shown in Fig. 9, the eccentric stud 38 is moved to the position shown by dotted lines in Fig. 2 so that when the slide 13 is shifted the pawl 40 will not be advanced a sufficient distance to engage the ratchet teeth 42. The knee lever is then moved in the proper direction to render operative the mechanism for giving the plaiting move-

130

ments to the grippers, which adjustment of the knee lever also returns the slide 13 to the position shown in Fig. 2, thereby advancing the work-pressers into operative position, and in addition restoring the fulcrum pin 55 to its position nearest the inner end of the lever 49 to effect longer movements of the wire feeding devices, and also through the connections described, locating the cutters farther from the anvil 121. It should be here stated, that prior to making these adjustments for lasting the shoe about the toe, the operator stops the machine. Such adjustments having been made the machine is re-started, and the lasting proceeds around the toe, the staples now formed being of a greater length than those which were formed while lasting at the side of the shoe in order that they may completely penetrate the increased amount of material due to the plaiting of the upper, and to the additional parts, such as toe stiffeners, which are sometimes added to the usual upper and linings at this portion of a shoe.

In case it is desired to discontinue the stapling operation at the toe and to secure the upper in lasted position by the usual continuous binder, the eccentric stud 38 is turned to a position opposite to that shown by dotted lines in Fig. 2, which projects the pawl 40 far enough to engage the ratchet teeth 42 of the driven clutch member when the slide 13 is moved into the position shown in Fig. 2, preliminary to lasting at the toe. The pawl, when in this position, yields against the action of the clutch member during its movements in one direction, but returns the clutch member to its original position on the return movement of the rack 63, so that successive forward rotative movements will not be imparted to the feed disk, and hence no wire will be supplied to the stapling mechanism. The lasting operation may then proceed in the usual manner, the operator securing the overworked upper by a binder, which if desired may have its ends anchored to the last by tacks, as shown in Fig. 8.

Fig. 10 of the drawings illustrates the end of a toe binder which has been secured to the last by staples. This may be accomplished, under the present invention, by holding an end of the wire *w* in proper position against the upper before re-starting the machine for lasting at the toe, and with the stud 38 adjusted as shown in Fig. 2, causing the machine to drive a single staple which will straddle the end of the wire, as shown. It will be understood, that to effect this result, the shoe will be presented at the proper angle to the end of the slide 103 to cause the staple to correctly engage the loose end of the wire. The machine being then brought to a stop, the stud 38 will be adjusted properly to discontinue the feed of

wire to the stapling mechanism, and the machine being re-started the lasting will proceed about the toe of the shoe, and the upper be secured in position by the binder until the point is reached where the other end of the binder is to be anchored to the last, when another staple will be driven to anchor said end in the same manner.

It is believed to have been sufficiently indicated in the foregoing description that an especially prominent feature of the invention lies in the capacity of the machine to insert single fastenings during the over-working operation, as each successive section of the upper is stretched over the sole margin, of a character and in a direction relative to the shoe bottom that will permit such fastenings to be used as the initial, and final, securing means for holding the upper in lasting position until the inseaming machine 85 permanently unites the upper, welt and innersole. These fastenings lie substantially parallel with and preferably above the plane of movement of the awl and needle of the inseaming machine where they 90 are not in a position to be struck by these elements, as is the case with the usual lasting tacks, or stay tacks, which are driven substantially perpendicular to the plane of the sole, and hence offer a substantial obstruction to the sewing operation.

Having thus described my invention, what I claim as new and desire to secure by Letters Patent of the United States is:—

1. A machine of the class described having, in combination, means for working an upper by repeated operations over a last having thereon a lipped innersole, staple forming mechanism including a reciprocating member arranged to force the over-worked upper against the lip, means for driving a staple from said member through the upper and lip to secure each successively overworked section of the upper in lasted position, and an abutment to enter the channel and clench the ends of the staples on the inside of the lip.

2. In a machine of the class described, the combination with grippers for tensioning an upper, of means for inserting staples 115 through the tensioned upper and the lip of an innersole and clenching the staples on the inner side of the lip, and means for applying pressure to clamp together the tensioned upper and the innersole lip adjacent 120 to the stapling point in advance of the staple inserting operation.

3. A machine of the class described having, in combination, grippers and actuating mechanism therefor arranged to pull 125 successive portions of an upper about a last and lay the upper upon an innersole having thereon a projection, and mechanism to drive separate fastenings through each successively overworked portion of the upper 130

and said projection in a direction substantially parallel with the plane of the inner-sole.

4. A machine of the class described having, in combination, grippers and actuating mechanism therefor arranged to pull successive portions of an upper about a last and lay the upper upon an innersole provided with a lip, means to force the upper into the angle formed by the feather edge and lip of the innersole, and means to drive separate fastenings through each successive portion of the overworked upper and the lip in a direction transverse to the lip.

5. A machine of the class described having, in combination, grippers and actuating mechanism therefor arranged to pull successive portions of an upper about a last and lay the upper upon an innersole provided with a lip, means to force the upper into the angle formed by the feather edge and lip of the innersole, means to drive staples in a direction transverse to the lip through each successively overworked portion of the upper and the lip as the work progresses, and means to clench the ends of the staples on the inside of the lip.

6. In a lasting machine, the combination with grippers for working an upper over a last having thereon a lipped innersole, of means to secure the overworked upper in position by independent fastenings which act transversely of the lip, means to cause the grippers to plait the upper, and means to discontinue the supply of fastenings during the plaiting operation.

7. In a lasting machine, the combination with grippers for working an upper over a last having thereon a lipped innersole, of a wiper arranged to be rendered operative for toe lasting, means for securing the overworked upper in position by independent fastenings which act transversely of the lip, and means for suspending the supply of said fastenings when the wiper is rendered operative.

8. In a lasting machine, the combination with grippers for working an upper over a last, of a wiper, means including a slide for rendering said wiper operative or inoperative, means for forming fastenings from wire and driving them through the overworked upper to secure it in position, feeding devices for the wire, and means connecting said slide and devices arranged to prevent or permit, at will, the supply of wire when the wiper is rendered operative.

9. In a lasting machine, the combination with grippers for working an upper over a last having thereon a lipped innersole, of a wiper, means including a slide for rendering said wiper operative or inoperative, means for forming staples from wire and driving them through the overworked upper and the lip of the innersole, feeding devices

for the wire, and means connecting said slide and devices arranged to prevent or permit, at will, the supply of wire when the wiper is rendered inoperative.

10. In a lasting machine, the combination with grippers for working an upper over a last having thereon a lipped innersole, of means to secure the overworked upper in position by independent fastenings which act transversely of the lip, a wiper, plaiting means for the upper, means for rendering the wiper and plaiting means operative or inoperative at will, and means arranged for simultaneous operation therewith to control the supply of said fastenings.

11. In a lasting machine, the combination with grippers for working an upper over a last having thereon a lipped innersole, of means to secure the overworked upper in position by independent fastenings which act transversely of the lip, a wiper, plaiting means for the upper, means for rendering the wiper and plaiting means operative or inoperative at will, and means capable of adjustment to suspend the supply of fastenings when the wiper and plaiting means are in operation, or to permit said supply, as desired.

12. In a lasting machine, the combination with means for working an upper over a last having thereon a lipped innersole, of means to secure the overworked upper in position by independent fastenings which act transversely of the lip, a wiper, means to render the wiper operative, and means to simultaneously control the length of said fastenings.

13. In a lasting machine, the combination with means for working an upper over a last having thereon a lipped innersole, of means to secure the overworked upper in position by fastenings which act transversely of the lip, a wiper, means to render the wiper operative or inoperative at will, and means to supply long fastenings when the wiper is operative, and short fastenings when the wiper is inoperative.

14. In a lasting machine, the combination with means for working an upper over a last having thereon a lipped innersole, of means to secure the overworked upper in position by fastenings which act transversely of the lip, plaiting means for the upper arranged to be rendered operative or inoperative, at will, and means to supply long fastenings when the plaiting means is operative, and short fastenings when the plaiting means is inoperative.

15. In a lasting machine, the combination with means for working an upper over a last having thereon a lipped innersole, of means to secure the overworked upper in position by fastenings which act transversely of the lip, a wiper and plaiting means for the upper arranged to be rendered operative

or inoperative, at will, and means to supply long fastenings when the wiper and plaiting means are operative and short fastenings when said parts are inoperative.

- 5 16. In a lasting machine, the combination with means for working an upper over a last, of means for forming fastenings of wire and driving the fastenings to secure the upper in overworked position, feeding devices for the wire, means for plaiting the upper, means to render the plaiting means operative or inoperative, at will, and controlling means for said devices constructed and arranged to cause them to feed wire for long fastenings when the plaiting means is operative, and to feed wire for short fastenings when the plaiting means is inoperative.
- 10 17. In a lasting machine, the combination with means for working an upper over a last, of means for forming fastenings of wire and driving the fastenings to secure the upper in overworked position, feeding devices for the wire, a wiper, means to render the wiper operative or inoperative, at will, and controlling means for said devices constructed and arranged to cause them to feed wire for long fastenings when the wiper is operative, and to feed wire for short fastenings when the wiper is inoperative.
- 15 18. In a lasting machine, the combination with means for working an upper over a last, of means for forming fastenings of wire and driving the fastenings to secure the upper in overworked position, feeding devices for the wire, a wiper and plaiting means for the upper arranged to be rendered operative or inoperative, at will, and controlling means for the feeding devices constructed and arranged to cause them to feed wire for long fastenings when the wiper and plaiting means are operative, and to feed wire for short fastenings when said parts are inoperative.

- 20 19. A lasting machine having, in combination, a wiper, means for forming fastenings from wire and for driving the fastenings to secure the upper in lasted position, feeding means for the wire including a lever having a movable fulcrum, means to render said wiper operative or inoperative, and a connection between the last-named means and the fulcrum of said lever to control the length of wire fed.
- 25 20. A lasting machine having, in combination, a wiper, means for forming staples from wire and for driving the staples to

secure the upper in lasted position, devices for feeding the wire to the staple-forming means, means for cutting the wire into suitable lengths for staples, means to render said wiper operative or inoperative, and connections between said last-named means and the wire feeding devices and cutting means constructed to insure the supply of wire for long staples when the wiper is operative and for short staples when the wiper is inoperative.

21. A lasting machine having, in combination, a wiper, a slide for moving the wiper into or out of operative position, staple forming and driving mechanism, devices for feeding wire to said mechanism including a clutch-member, and a yielding pawl having connection with said slide and arranged to be advanced so as to engage said clutch-member and thereby suspend the feeding of wire when the wiper is moved into operative position.

22. A lasting machine having, in combination, a wiper, a wiper-controlling member for moving the wiper into or out of operative position, means for forming staples from wire including an anvil, means for driving staples to secure the upper in lasted position, devices for feeding wire to the staple-forming means including a lever having a movable fulcrum, cutting means for the wire mounted for movement relatively to said anvil, and connections from said member to the movable fulcrum and cutting means for controlling the length of the staples formed in accordance with the position of said wiper.

23. A lasting machine having, in combination, a wiper, a slide for moving the wiper into or out of operative position, staple forming and driving mechanism, devices for feeding wire to said mechanism including a clutch member, a yielding pawl for engaging the clutch member to suspend the supply of wire, and connections between said slide and pawl including an eccentric pin arranged for adjustment to cause said pawl to engage the clutch member when the wiper is moved into operative position or to prevent such engagement, at will.

In testimony whereof I have signed my name to this specification in the presence of two subscribing witnesses.

EDWARD A. STIGGINS.
